UNITED STATES PATENT OFFICE.

ERNEST WILLIAM COTTER, OF SYDENHAM, LONDON, AND ERNEST TROUGHTON, OF BROCKLEY, LONDON, ENGLAND, ASSIGNEES TO J. STONE & COMPANY LIMITED, OF DEPTFORD, ENGLAND.

WINDOW AND VENTILATOR.

Application filed November 26, 1920. Serial No. 426,555.

To all whom it may concern:

Be it known that we, ERNEST WILLIAM COTTER, a subject of the King of Great Britain, residing at 5 Kingsthorpe Road, Sydenham, London, S. E. 26, England, and ERNEST TROUGHTON, a subject of the King of Great Britain, residing at 100 Adelaide Road, Brockley, London, S. E. 4, England, have invented certain new and useful Improvements in and Connected with Windows and Ventilators, of which the following is a specification.

This invention comprises improvements in and connected with windows and ventilators and has for its principal object to provide a simple and efficient opening and closing mechanism which is applicable for operating ventilator sashes or devices and which can be conveniently operated.

Also, the object of the invention is to adapt the said opening and closing mechanism for application to that type of window in which upper and lower sashes are provided at the sides with toothed racks engaging or meshing with pinions, so that one sash balances the other. In this adaptation, the mechanism may be used for moving one sash a little to give a ventilation opening without causing movement of the other sash, in addition to serving for balancing one sash against the other and producing simultaneous and opposite motion of such sashes in the manner known in self-balancing windows.

A further object of the invention is to improve the construction of windows of the self-balancing type and other subsidiary objects are to provide for the tightening and fastening of the sashes in a simple and effective manner, and also to enable one sash, in emergency, to be fully opened without disturbing the other sash.

According to this invention the opening and closing mechanism comprises opposed racks and intermediate pinions meshing with the racks the pinions being mounted so as to have, under the influence of operating levers, a limited rolling motion along one of the racks in addition to revolving motion, thereby increasing the movement of the ventilator or sash as compared with the amount of movement which would be produced if the pinions revolved on a fixed pivot. The pinions may be of the ordinary

simple construction, or differential pinions 55 may be used having one diameter in mesh with one rack and a different diameter in mesh with the other rack. When the mechanism is adapted for application to self-balancing sashes, each sash is fitted with side 60 racks meshing with the intermediate pinions aforesaid and the mechanism not only permits of opening one of the sashes to a predetermined extent without disturbing the other sash, for the purpose of obtaining a 65 ventilating opening, but it also permits of the two sashes being opened or closed simultaneously after the manner of sashes in self-balancing windows. In the case of self-balancing sashes being used, the two 70 sashes may be separated by an interposed guide frame and the members of the latter may be inserted or seated in a groove formed around the interior of the window frame. In the case of a metal window, the interposed frame may be of T-section metal and may be secured by fastening the head of the T against the interior of the window frame, or it may be integral with the window 75 frame.

In order to enable this invention to be readily understood, reference is made to the accompanying drawing, in which:

Figure 1 is an elevation of a window fitted with these improvements and as seen from 85 the interior of a room or compartment.

Figure 2 is a central vertical section of Figure 1.

Figure 3 is a horizontal section of Figure 2 at the part where the pinion is mounted. 90

Figure 4 is a vertical section and similar to the top part of Figure 2, but showing a modification suitable for use in the construction of metal windows.

Figure 5 is a section similar to Figure 95 3 but of a metal window such as is seen in Figure 4.

Figure 6 is a view similar to the middle part of Figure 2, but showing the operating parts in the position for producing a 100 ventilation opening of the window.

Figure 7 is a sectional side elevation of a modified mechanism and Figure 8 is a section of Figure 7, the plane of the section being parallel with the plane of the window. 105

Figures 9 and 10 correspond with Figures 7 and 8 respectively but illustrate another modification.

Figures 11 and 12 also correspond with Figures 7 and 8 respectively and illustrate yet another modification.

Figures 13 and 14 are side and front elevations respectively of a lever mechanism such as is seen in Figures 2 and 6.

Figure 15 is a side elevation and Figure 16 is a front elevation, with a part broken away, illustrating a modification for enabling one sash to be fully opened without disturbing the other as above referred to.

Figure 17 is a sectional side elevation illustrating the application of a differential pinion for meshing with the racks of self-balancing sashes, and

Figure 18 is a horizontal section of Figure 17.

The opening and closing mechanism embodying these improvements will first be described in connection with a window of the so-called self-balancing sash type, but, as will appear, by assuming that the lower sash is a fixture, the functioning of the improved opening and closing mechanism will be clear, apart from its adaption for use with self-balancing sashes. Figures 1 to 5 illustrate self-balancing sash windows in which the upper sash *a* and the lower sash *b*, both of which are slidable up and down in the window frame *c*, are fitted with racks, the former with a rack *d* and the latter with a rack *e*. These racks are spaced apart so that they may mutually mesh with an intermediate pinion *f* and in this manner the weight of the top sash is balanced by the lower sash in known manner. Now it is advantageous, particularly on board ship, to be able to open the top sash to a small extent to give a ventilating opening, and in order that this may be accomplished without also opening the bottom sash, the improved opening and closing mechanism is introduced, as will now be described. In one arrangement, and as will be seen from Figures 2, 3, 6, 13 and 14, the pinions *f*, at each side of the window are mounted on stub axles *o* formed or fitted on the short arms *p* of two-armed levers formed with lateral pivotal projections *q*. The long arms *r* of these levers pass through slot openings *s*, Figure 1, at the sides of the frame and into the compartment, room, deckhouse or cabin or other interior, the pivotal projections taking into short horizontal guides provided at the sides of the window. In wood frame windows, slots may be formed in the side members of the frame and guide sockets *t*; see particularly Figure 14, may be inserted into and secured in the slots. The long arms *r* of the levers may be at an angle of about 150° with the short arms *p* so that when the short arms *p* stand vertically as in Figures 2 and 13, the long arms *r* extend downwardly and outwardly through the slot openings *s* to the interior

of the room or the like. When the short arm *p* is vertical, the pinion *f* is supported at its highest elevation and both sashes are closed. If a ventilation opening only is required, a person takes hold of the handles *u* at the ends of the long arms *r* of the levers and lifts the latter thereby turning the levers about their pivots *q*. As the pinions *f* lie between the appropriate racks *d* and *e* it is only possible for these pinions to move downwardly as the short arms *p* are turned downwardly by the lifting of the long arms, that is to say, it is not possible for the stub axles *o* at the ends of the short arms to described a curve as the short arms are turned. Consequently, as the short arms *p* turn from the vertical position to a horizontal position, the pivots *q* move along the horizontal guides *t* until the opposite ends of such guides are reached, and as the downward movement of the short arms *p* is continued until the long arms are arrested by coming against the window frame as seen in Figure 6, the said short arms *p* turn slightly downwardly and the pivots *q* move along the guides for a short distance towards their initial position, all as will be readily understood from a comparison of Figures 2 and 6 which show the parts in the two extreme positions. As the pinions *f* are lowered, the racks *d* of the upper sashes *a*, and these sashes also, are lowered to the same extent as the pinions *f* plus an additional amount due to the pinions *f* rolling upon the racks *e* of the lower sashes *b* which do not move but remain in the closed position. In this manner, the upper sash is lowered to give a ventilating opening without disturbing the lower sash. If the lower sash *b* be fixedly secured so that it is impossible for it to be opened, then the mechanism above described simply operates as an opening and closing mechanism for adjusting the sash *a* to give a desired ventilation opening, but if the sash *b* is free to be opened, then further depression of the upper sash *a* will now produce a corresponding raising of the lower sash *b* owing to the rack and pinion transmission and, conversely, the raising of the lower sash *b* will produce a lowering of the upper sash *a*, owing to the meshing of the racks *d* and *e* with the pinions *f* in the well-known manner. The sash *b* may be fitted with finger grips *v*, Figures 1 and 2 for facilitating the raising thereof, or any other convenient means may be fitted to either of the sashes for facilitating their manipulation. If desired, of course, the simultaneous opening of the two sashes from the closed position may be proceeded with at once without first operating the levers *r* to lower the pinions *f* and the upper sash *a* alone. Between the sashes is interposed a guide frame *g* which may extend around all interior sides of the

window frame *c*. As seen in Figure 2, the members of this guide frame *g* are composed of flat strips which are secured by one edge in a groove *h* in the interior surfaces of the window frame *c*. This arrangement is suitable for windows made of wood. For metal windows, the guide frame *g* may be composed of the webs or flanges of T-section bars *j*, as seen in Figure 4, and the heads of the T-bars may be bolted or connected to the interior surfaces of the window frame *c*. In order to retain the sashes *a* and *b* in the closed or fully or partly open, position, clamping screws *l* may be screwed through suitable nuts *m* let into the window frame and so as to press against the frame *g* which latter may be fitted with small wear plates *n* at the points where the screws *l* bear.

20 In the modifications now about to be described with reference to Figures 7 to 12, it will be understood that the mechanisms may be applied for operating ventilators or ventilator sashes only by fixedly mounting the racks *e* as aforesaid or they may be applied for operating self-balancing sashes by mounting the racks *e* on a lower sash and the racks *d* on an upper sash.

According to the modification illustrated 30 in Figures 7 and 8, a short link *w* may be pivoted on a fixed pin *x* supported in a bracket *y* attached to the window frame, and in the closed position of the sashes the link *w* may extend upwardly at an angle, 35 as seen in Figure 7. The link *w* is formed with a slot *w'* to receive the end of the appropriate stub axle *o*, it being understood, of course, that there may be a similar mechanism at each side of the window. The 40 forked or recessed end *z* of a long lever handle 1 embraces the end of the link *w* and is pivotally connected thereto by a hollow pivot pin 2 screwed into the lever and passing into the slot *w'* of the link *w* which slot 45 is enlarged at one end for the reception of the said pin 2. Part of the hollow pin 2 is removed at 3 so that the stub axle *o* can pass into and out of the hollow of the pin 2 which hollow constitutes a continuation of 50 the slot *w'*. The end of the link *w* is formed with a flat 4 indicated in dotted line in Figure 7, and the surface of the recess in the forked end of the lever 1 is formed with two flats at an angle to one another, also as indicated by dotted line at 5 in Figure 7. These flats 4 and 5 form contacting surfaces, 55 permitting of turning the lever handle 1 through a small angle before bringing one or other of the angular surfaces 5 of the lever 1 into contact with the flat surface 4 of the link. The hub or forked end *z* of the lever 1 may be formed with a projection 6 adapted for engaging with recesses 7 and 8, see Figure 7, in the bracket *y* in which the 60 pivot *x* of the link *w* is mounted. In the

closed position of the sashes, the link *w* and lever 1 extend upwardly, as seen in Figure 7, at an angle from the vertical and the lever 1 extends through the window frame so as to be accessible to persons in the room, cabin 70 or other space. In this position, the projection 6 on the lever 1 rests in the recess 7 of the bracket *y* and is locked in this position thereby, the engagement of the flat surfaces at 4 and 5 causing the locking of 75 the link *w* also, so that the pinion *f* is locked in the elevated position. To obtain a ventilating opening, the lever 1 is first raised a little so as to remove the locking projection 6 from engagement with the recess 7 in the 80 bracket *y*, and then by keeping the surfaces at 4, 5 in engagement by pressing on the lever 1 and at the same time lowering the lever, the link *w* and pinion *f* are lowered, 85 thereby lowering the racks of the upper sash and the latter also, as described with reference to the first construction. When the lever 1 is released after bringing the upper sash to the partly open and ventilating position, the projection 6 on the lever may enter the recess 8 of the bracket and so lock the link in its lower or downwardly inclined position. In this position of the parts, 90 movement imparted to either of the sashes will produce corresponding and opposite 95 movement of the other sash through the gearing of the racks and pinions, excepting that, if the parts be in this position with the lower sash closed, and the lever 1 be raised, the upper sash will be closed as will 100 be readily understood.

According to the modification illustrated in Figures 9 and 10, a right-angled lever 9 is formed with a lateral projection 10 at its angle, this projection 10 taking into a vertical slot 11 formed in, say, a metal plate 12 attached to a side member of the window frame *c*. One arm of this lever 9 extends horizontally through a slot in the window frame and the other extends vertically upwards and has the pinion *f* revolvably mounted at its upper end. The vertical slot 11 is formed with a short lateral extension 11^a at 110 its upper end and with an extension 11^b at its lower end for the projection 10 to enter at the end of a raising or lowering movement as the case may be. In the raised or closed position of the upper sash, the projection 10 rests in the slot extension 11^a at 115 the top of the slot 11. To produce a ventilating opening of the upper sash, the horizontal arm of the lever 9 is pushed inwardly a little so that the projection 10 may descend in the vertical slot 11, the lever 9, pinion *f* and upper sash and rack being 120 lowered until the projection 10 comes to the bottom of the slot 11. Whereupon the lever 9 is pushed inwardly a little to bring the projection 10 into the lateral extension 11^b at 125 the bottom of the slot. Thereafter, the 130

movement of one sash will be communicated to the other sash through the rack and pinion gearing, as in the other constructions, or, if the lower sash is in the closed position, the upper sash may be closed by the raising of the lever 9 and the entering of the projection 10 into the upper extension 11^a of the slot 11 will secure the upper sash in the closed position.

According to the further modification illustrated in Figures 11 and 12, the axle of the pinion *f* is carried eccentrically in a disc 13 mounted in horizontal guides 14 on a side member of the window frame *c*, the disc 13 having a central axle or projection 15 extending through a horizontal slot 16 formed in a guide fitting 17 on the frame *c*. The end of the axle or projection 15 extends to the exterior of the window frame *c* and may be formed with a square 18 so that it can be turned only by the application of a key or the like. The turning of the disc 13 in one direction or the other produces a raising or lowering of the pinion *f* in order to open or close the upper sash to the extent of the ventilating opening, the disc 13 moving along the guide 14 and the axle 15 moving along the slot 16 during such raising or lowering of the pinion *f* as will be readily understood from the drawing. In the event of part of the frame *c* not standing out clear of the wall so that the square end 18 is accessible, a recess could be formed in the wall for enabling the box head of a suitable spanner to be inserted and applied to the square end 18.

Disconnectable means may be provided for permitting one sash to be fully opened without opening the other sash. In one suitable arrangement permitting of this, and as illustrated in Figures 15 and 16 the two racks *d* and *e* are geared together by a train of three pinions 19, 20 and 21 carried on a stud plate 22, the top pinion 19 meshing with the upper rack *d* and the bottom pinion 21 meshing with the lower rack *e* and both pinions being in mesh also with the centre pinion 20. The stud 23 carrying the centre pinion 20 passes through the stud plate 22 and is secured to, or is integral with the operating lever 24 which, for the production of a ventilating opening, is manipulated in the same manner as in the above described arrangements comprising single transmission pinions, as for example the arrangement described with reference to Figures 2, 3, 6, 13 and 14. In this construction, however, the stud 25 of the top pinion 19 forms the pivot for a second lever 26, and the latter has operative engagement with a vertically slidable plate 27, as, for example, by engaging a slot 28 in the lever 26 with a pin or projection 29 on the plate 27. The latter is formed with an aperture 30 of such a configuration as to

receive the stud plate 22 and to provide inclined edges 31 and 32 for engaging with an inclined edge on the right hand side of the stud plate 22 above the stud 23 of the centre pinion 20 and with an inclined edge 70 on the left hand side of the stud plate 22 below the centre pinion. The engagement of these edges, as seen in Figure 15, prevents the stud plate 22 from being swung as a lever about the axle of the top pinion 19 as a pivot, excepting when the slidable plate 27 is moved relatively to the stud plate 22. In this construction, the manipulation of the operating lever 24 for producing a ventilating opening causes the simultaneous downward movement of the three pinions 19, 20 and 21, the stud plate 22, the second lever 26, and the slidable plate 27, the bottom pinion 21 rolling on the lower rack *e* and the top pinion not only lowering 85 the upper rack *d* by reason of its descent, but in addition, by reason of the revolving motion imparted to it by the lower pinion 21. When it is desired to have a full opening of the lower sash, as in an emergency when a person may desire to escape through the window, the ventilation lever 24 is brought to its closed position, if it is not already in that position. The second lever 26 is then turned about its pivot 25, the connection between the pin 29 and slot 28 causing the slidable plate 27 to descend. As the stud plate 22 does not partake in this descent, the relative motion between the plates 27 and 22 causes the upper inclined edges at 31 to engage and to swing the stud plate 22 about the stud 25 of the top pinion 19. In this manner, the bottom pinion 21 is withdrawn out of mesh with the lower rack *e* and at the same time the centre pinion 20 is caused to mesh with the top rack. As both the top pinion 19 and the centre pinion 20 are now in mesh with the upper rack, the upper sash is locked and held in the closed position leaving the lower sash free to be lifted to the fullest extent. When the lower sash is closed again, the second lever 26 is reversed to bring the pinions 20 and 21 back to their normal position for transmitting motion between the racks *d* and *e*. To prevent the second lever 26 from being used, except in case of necessity or emergency, it can be locked to the window frame by a clip device. As will be noted from Figure 16 both levers 24 and 26 work in the same slot so that the lever 26 cannot be lowered while the lever 24 is in the raised position giving a ventilating opening of the upper sash. By reversing the arrangement of the slidable plate 27, the disconnectable means could be adapted for permitting the upper sash to be fully lowered without raising the lower sash.

Instead of using a single pinion *f* as in Figures 1 to 14 a double or differential

pinion f f' may be employed as seen in Figures 17 and 18. In this example the pinion f is of larger diameter than the pinion f' and the former meshes with the rack e of the lower sash while the latter meshes with the rack d of the upper sash. By this means the movement of the upper sash will be less than that of the lower sash when simultaneous lowering of the upper sash and raising of the lower sash takes place. This double or differential pinion is shown mounted in a similar manner to the pinion f in Figures 2, 6, 13 and 14, but it will be apparent that a double or differential pinion might be substituted for the single pinions in Figures 7 to 12. These differential pinions may be used in self-balancing windows when one sash is larger or heavier than another, or when for any reason unequal opening movements of the two sashes is desired. Naturally the larger pinion f may mesh with the rack of the upper sash and the smaller pinion f' with the rack of the lower sash.

25 We claim:—

1. A window or ventilator opening and closing mechanism comprising a rack fixed on the member to be operated, a rack fixed on an adjacent support, a pinion in mesh 30 with the racks, a carrier revolvably supporting said pinion, and a lever for manually operating said carrier to effect the opening and closing of the window and having a limited motion for enabling said pinion to 35 roll on the secondly named rack.

2. A window or ventilator opening and closing mechanism, comprising a rack fixed on the sliding member to be operated, a rack fixed on an adjacent support, a pinion in 40 mesh with both racks, an oscillatory operative lever fitted with a revolute mounting for said pinion and with a pivot, and guides for said pivot perpendicular to said racks, said lever being adapted to be manually operated to move said pivot along said guides.

45 3. A window or ventilator opening and closing mechanism, comprising a rack fixed on the sliding member to be operated, a rack fixed on an adjacent support, a pinion meshing 50 with the said racks, a lever arm fitted

with a revolute mounting for said pinion and with a pivot, guides for said pivot perpendicular to said racks, and an oscillatory hand lever operatively connected with said arm and adapted to turn and move the latter 55 in said guides.

4. A window or ventilator opening and closing mechanism, comprising a rack fixed on the sliding member to be operated, a rack fixed on an adjacent support, a pinion meshing between the racks, a manually operated oscillatory lever carrying and revolvably supporting said pinion, and guides perpendicular to said racks and adapted to slidably support said pinion carrying lever.

5. A window or ventilator opening and closing mechanism comprising opposed racks, a pinion meshing between said racks, a manually operated oscillatory member carrying and revolvably supporting said pinion, and a support for said oscillatory member adapted to permit lateral movement to be imparted thereto.

6. A window or ventilator opening and closing mechanism, comprising opposed 75 racks, a pinion between and meshing with both racks, a bent lever arm, an axle pin at one end of said arm for revolvably mounting said pinion, a pivot projection mounted intermediately on said arm, and a slide-way 80 engaging said projection and mounted on the window framing perpendicularly to said racks.

7. A window or ventilator opening and closing mechanism comprising opposed 85 racks one of said racks being fixed to a sliding sash and the other being fixed to an adjacent support, a pinion between and meshing with both racks, a bent lever comprising a long arm and a short arm a revolute mounting for said pinion at the free end of the short arm, a pivot projection at the junction between said arms, and a slide way fitted on the window framing perpendicularly to said racks and adapted to receive 90 said pivot projection, said lever being normally supported so that its long arm is accessible for manual operation.

ERNEST WILLIAM COTTER.
ERNEST TROUGHTON.
